UNITED STATES PATENT OFFICE.

WILLIAM F. DECKER, OF NEW YORK, N. Y.

DESIGN FOR A CASING FOR UPRIGHT PIANOFORTES.

SPECIFICATION forming part of Design No. 21,995, dated November 15, 1892.

Application filed September 28, 1892. Serial No. 447,179. Term of patent 14 years.

To all whom it may concern:

Be it known that I, WILLIAM F. DECKER, a citizen of the United States, residing in the city, county, and State of New York, have invented and produced a new and original Design for an Upright - Pianoforte Casing, of which the following is a specification, reference being had to the accompanying drawing, which represents a perspective view of an upright-pianoforte casing having my design.

This invention consists in a new configuration of an upright - pianoforte casing, the principal feature of invention residing in the brackets or bracket-like projections located between the ends of the keyboard and the ends of the casing, leaving panels between the ends of the casing and said brackets, substantially as shown.

In the drawing, the letter A represents the main casing of an upright piano. 20
B is the keyboard.

C C are brackets flanking the ends of the keyboard, and a are panels between the brackets and the ends of the casing and aligned with the ornamented ends of the casing, which 25 are above the plane of the brackets.

What I claim is—

The design for an upright-pianoforte casing, substantially as shown.

WILLIAM F. DECKER.
